UNITED STATES PATENT OFFICE.

RAYMOND L. HAWKINS, OF DETROIT, MICHIGAN, ASSIGNOR TO LONG MANUFACTURING COMPANY, OF DETROIT, MICHIGAN, A CORPORATION OF MICHIGAN.

RADIATOR.

1,379,015.

Specification of Letters Patent.

Patented May 24, 1921.

Application filed April 28, 1917, Serial No. 165,071. Renewed November 21, 1918. Serial No. 263,635.

To all whom it may concern:

Be it known that I, RAYMOND L. HAWKINS, a citizen of the United States, residing at Detroit, county of Wayne, and State of Michigan, have invented certain new and useful Improvements in Radiators, of which the following is a full, clear, and exact description.

This invention relates to certain new and useful improvements in radiator construction and has for its object the provision of a radiator which is simple in construction, efficient in the dissipation of heat, easily manufactured and less susceptible to developing leaks when in use.

In one embodiment of my improved construction, vertical flat water tubes are used. These tubes are semi-hexagonally corrugated at each edge and when assembled in place to form the core their tubes are separated by separating members which are likewise semi-hexagonally corrugated at their ends and intermediate the ends these members are shaped to form baffles which direct the air passing through the core against the vertical walls of the water tubes. It will be understood that the assembly of semi-hexagonally corrugated tubes and spacing members in the complete core give the core an appearance at the front and back of being a hexagonal cellular radiator, whereas in fact the front and back portions alone are of hexagonal contour. The intermediate portions between the front and back are straight vertical tubes, whereby the cost of manufacture is materially reduced. The resulting core has greater strength than a regular flat tube radiator and is less liable to develop leaks when in use, as there is no water in the tubes immediately adjacent the front and rear thereof. These portions of the tubes are crimped together, as will be explained in further detail hereinafter.

Other objects of the present invention will be pointed out in more detail in the accompanying specification and more particularly defined in the appended claims.

In the drawings Figure 1 shows in central section a radiator embodying my invention.

Fig. 2 is a front view of a portion of the core.

Fig. 3 is a sectional view taken on line 3-3 of Fig. 2.

Fig. 4 is a sectional view taken on line 4-4 of Fig. 1.

Fig. 5 is a detail view of one of the vertical water tubes.

Fig. 6 is a detail view of one of the spacing members.

In more detail, the radiator comprises a lower tank 10, upper tank 11, filler tube 12, and shell 13.

The core which is disposed between the upper and lower tanks is built up of a number of elements, namely, water tubes and spacer members.

The water tube shown in Fig. 5 is made from a single piece of sheet metal bent in such a way as to form spaced apart walls 14 and 15, forming a hollow flat tube 16. In order to prevent the tube from collapsing, I may provide longitudinal crimps therein or preferably I provide abutting buttons 17 (see Fig. 3). One edge of the tube has the usual overlapping seam 18. When the flat tube has been completed the edges thereof are crushed together and deformed into semi-hexagonal contour as clearly shown at 19 in Fig. 5. The semi-hexagonal portions are also provided with a series of cupped depressions and projections 20.

The spacer member is shown in Fig. 6 and has the edges shaped to semi-hexagonal form, as shown at 21. On these hexagonal portions I likewise provide depressions and projections 22. Intermediate the semi-hexagonal edges of the spacer strip the metal is sheared out and the remaining bridging strips 23 are turned to substantially a right angle with the plane of the strip.

The spacing members and water tube elements are then assembled together side by side in such a manner that the semi-hexagonal edge of a spacing member is disposed complementary to the semi-hexagonal edge of the tube element. The cupper depressions and projections 21 rest with the corresponding buttons and depressions 19 and facilitate the assembly. The core then comprises alternate spacers and water tubes, the metal of the deformed ends forming a number of hexagons. (See Fig. 3.) The core is then soldered by dipping the hexagonal end portions in solder.

The resulting core has the well known pleasing appearance of a hexagon cellular radiator when examined from the front or rear. The construction is also very rigid due to the hexagonal edges. Furthermore, since there is no water at the extreme forward or rear-

ward edge of the water tube, small dents in the face of the core do not cause leakage. The bridging members 23 serve as combined spacers for the water tubes and as baffles and 5 stir the air passing through the tubes. They also serve as heat radiating fins.

When the core is completed the upper and lower edges of the tubes and spacers are turned over with their edges overlapping, as 10 shown at 25 in Fig. 2. These portions form a header plate and are soldered together in the usual manner. The upper and lower tanks have inturned edges 26 and 27 and it is these inturned edges that are attached to 15 the core. The weight of the tanks is therefore supported at the front and rear directly over the hexagonal portion of the core which it will be understood is exceedingly rigid.

My invention is adapted to be modified in 20 various ways which will occur to those skilled in the art. What I claim as my invention is more particularly pointed out in the appended claims.

I claim:

25 1. A radiator core comprising a series of flat vertical tubes, semi-hexagonally corrugated at each edge thereof only, a series of intermediate spacing members semi-hexagonally corrugated at each edge thereof only, 30 said tubes and spacing members being so disposed relatively to one another as to form a series of hexagonal apertures at each face of the core.

2. A radiator core comprising a series of 35 flat vertical tubes having a plurality of semi-hexagonal corrugations at each edge thereof only, a series of spacing members, having a plurality of semi-hexagonal corrugations at each edge thereof only, each of said spacing 40 members being disposed between a pair of said tubes in such a manner as to form with the semi-hexagonal edges of the tubes a series of hexagons at each end of the radiator, whereby the front and rear faces of the 45 core have the appearance and strength of a hexagonal cellular radiator.

3. A radiator core comprising a series of flat vertical tubes corrugated at each edge thereof only, and a series of intermediate

spacing members correspondingly corrugated at each edge thereof only, the corrugations of said spacing members being alternately complementary to those of the tubes whereby a series of cellular apertures is formed at each face of the core. 50

4. A radiator core comprising a series of flat vertical tubes corrugated at each edge thereof only, correspondingly corrugated strips intermediate the corrugated edge portions of said water tubes, the corrugations of said strips being alternately complementary to those of the adjacent tubes whereby a series of cellular apertures is formed at each face of the core. 55

5. A radiator core comprising a series of flat vertical tubes corrugated at each edge thereof only, a series of correspondingly corrugated spacing strips arranged intermediate the corrugated portions of said tubes, the corrugations of said strips being alternately complementary to those of the adjacent tubes, whereby a series of cellular apertures is formed at each face of the core, and radiating fins extending integrally between the spacing strips adjacent the two faces of the 70 radiator. 75

6. A radiator core comprising a series of flat vertical tubes, spacer strips engaging the edge portions only of said tubes, and radiating fins extending between the water tubes 80 and integrally connecting the spacing strips adjacent opposed faces of the core, and supported solely by said strips and out of contact with the water tubes.

7. A spacer member for a water tube 85 radiator comprising corrugated strips for engagement, respectively, between the front and rear edges of the water tubes and integral fins connecting said strips deflected to the transverse relation to said strips. 90

8. A spacer member for a water tube comprising front and rear strips forming the spacer members proper and fins bent transversely to said strips and spaced longitudinally of the latter, forming the sole connection between said strips. 95

In testimony whereof I affix my signature.
RAYMOND L. HAWKINS.
